(57) **CLAIM**

The ornamental design for a rescue working channel for kyphoplasty, as shown and described.

DESCRIPTION

FIG. 1 is a front perspective view of a rescue working channel for kyphoplasty showing an insert needle and a needle holding pipe joined together;

FIG. 2 is a bottom perspective view thereof;

FIG. 3 is a front elevational view thereof, the rear elevational view being a mirror image;

FIG. 4 is a left-side elevational view thereof, the right-side elevational view being a mirror image;

FIG. 5 is a top plan view thereof;

FIG. 6 is a bottom plan view thereof;

FIG. 7 is an exploded view thereof, showing the insert needle and the needle holding pipe; and,

FIG. 8 is an assembled view thereof, showing the insert needle and the needle holding pipe partially joined together.

1 Claim, 7 Drawing Sheets
